UNITED STATES PATENT OFFICE.

JAMES A. MEADS, OF SACRAMENTO, CALIFORNIA.

AUTOMOBILE BOILER.

Application filed March 23, 1921. Serial No. 454,604.

To all whom it may concern:

Be it known that I, JAMES A. MEADS, a citizen of the United States, residing at Sacramento, in the county of Sacramento and State of California, have invented new and useful Improvements in Automobile Boilers, of which the following is a specification.

This invention relates to a boiler, and particularly pertains to a steam boiler for use in automobiles and the like.

It is the principal object of the present invention to provide a boiler for efficiently generating steam, which boiler consists of a plurality of detachable and interchangeable units adapted to provide water circulating means, said units being further constructed to insure that the maximum heat will be imparted to the water.

The invention contemplates the use of headers carrying a plurality of tube units, the individual tube elements of which have a central passageway therethrough to form flues through which heat may travel causing heat to pass through and around the tubes.

The invention is illustrated by way of example in the accompanying drawings, in which

Fig. 1 is a view in vertical section and elevation through the boiler, with parts broken away to more clearly disclose the construction of the tube units,

Fig. 2 is a view in transverse vertical section through the boiler near one side thereof showing the general arrangement of the headers and the tube units.

Referring more particularly to the drawings, 10 indicates a fire box within which heat may be generated by any suitable means. As shown in Fig. 1 an oil burner 11 is provided. Disposed directly above the fire box and at the opposite ends thereof are lower headers 12. One of these headers is positioned at the front and the other at the rear of the fire box. Parallel to these members and a considerable distance thereabove are upper headers 13. It is understood that these headers are hollow and provide distributing conduits for water and vapor. One of the lower headers is equipped with a water inlet pipe 14. The complementary upper header is equipped with an outlet pipe 15. These pipes are valve controlled and, as shown in Fig. 1, a

water level gauge 16 is connected from one pipe to the other, thus indicating the water level within the boiler.

The headers are provided with communicating conduits for a plurality of tube units 17. These units each comprise parallel top and bottom pipes 18 and 19 respectively vertical water tubes 20 and flue pipes 21. The opposite ends of the pipes 18 and 19 are threaded and fitted with unions 22 by which these members are detachably secured to tubular extensions 23 communicating with and projecting from the headers between which the units are disposed. The water tubes or columns 20 are welded through openings in the pipes 18 and 19 and are spaced equidistant therealong. Extending upwardly through the columns and concentric therewith are the flue pipes 21. These flue pipes are of an outside diameter relative to the inside diameter of the columns so as to provide a space for the water columns within the tubes and around the flue pipes. The lower ends of the flue pipes are secured through the bottom of the member 19, while the upper ends extend through the top of the cross member 18. These flue pipes are welded in position. It will therefore be evident that the heat and products of combustion produced by a source of heat such as the burner 11 will pass upwardly through and around the water columns in the various tube units, after which it may pass out through a flue 24 in the top of an enclosing shell 25.

The vapor generated within the boiler does not pass directly therefrom but flows out into the upper headers 13 and from thence through the pipes 25 into a steam dome 26. A steam outlet pipe 27 is connected with this dome at some convenient point. A plurality of washout plugs 28 are mounted in threaded openings arranged along the headers so that the individual units may be cleaned when desired.

In the operation of the present invention the boiler is assembled as shown in the drawing, after which it is filled to a desired height and a heat generating unit set in action to deliver heat to the fire box 10. This heat will circulate upwardly within the shell and will pass through and around the water columns of the various tube units, thus heating the columns of water both from the inside and outside of the units,

and due to the fact that the volume of water around the column and between the inner and outer walls is relatively small the water may be rapidly raised and maintained at a high temperature. When any of the various units become clogged with foreign material the corresponding plug 28 may be removed and the unit washed out. If repair is required the unions 22 may be readily disconnected to permit the removal of the desired unit, and in this case it is possible to cap the corresponding extensions 23 so that the boiler may continue operation without the damaged tube unit.

15 It will thus be seen that the device here disclosed is decidedly simple in operation and that due to its construction the various parts may be readily interchanged or renewed, at the same time providing a boiler 20 within which steam may be rapidly generated and an efficient consumption of heat brought about.

While I have shown the preferred form 25 of my invention as now known to me, it will be understood that various changes might be made in the combination, construction and arrangement of parts by those skilled in the art without departing from the spirit of the invention as claimed.

30 Having thus described my invention, what

I claim and desire to secure by Letters Patent is—

In a steam generator for vehicles, a plurality of vertically disposed tube units arranged at spaced distances apart and in alignment with each other, each of said units comprising horizontal upper and lower tubes and a plurality of vertically disposed tubes connected therewith and interposed therebetween to establish communication between said horizontal tubes, horizontal headers arranged at right angles to the tube units and disposed along opposite ends of the upper and lower horizontal tubes to establish communication therebetween, detachable 45 connections between the ends of the horizontal tubes of each unit and the headers whereby the units may be individually removed without disturbing the other units, a flue pipe disposed concentrically within each vertical tube, said flue pipes extending through and across the horizontal tubes, a water inlet connection for the lower headers, a steam dome, connections between the steam dome and the upper headers, and removable 50 plugs in the sides of one upper and one lower header, said plugs being disposed in alignment with the horizontal tubes of the tube units to permit cleaning thereof.

JAMES A. MEADS.
